DESIGN FOR A GRINDING MACHINE

Charles H. Antrim, Grand Rapids, Mich., assignor to Hammond Machinery Builders, Inc., Kalamazoo, Mich., a corporation of Michigan

Application October 26, 1942, Serial No. 108,616

Term of patent 14 years

To all whom it may concern:

Be it known that I, Charles H. Antrim, a citizen of the United States, residing at Grand Rapids, in the county of Kent and State of Michigan, have invented a new, original, and ornamental Design for Grinding Machines, of which the following is a specification, reference being had to the accompanying drawing, forming part thereof, in which:

Fig. 1 is a front perspective view, and

Fig. 2 is a rear perspective view on a reduced scale of a grinding machine, showing my new design.

I claim:

The ornamental design for a grinding machine, as shown.

CHARLES H. ANTRIM.
